CLAIM

The ornamental design for a nipple for a nursing bottle, as shown and described.

DESCRIPTION

FIG. 1. is a top-front perspective view of a first embodiment of a nipple for baby bottle, showing our new design;

FIG. 2 is a top plan view thereof;

FIG. 3 is a front elevation view thereof;

FIG. 4 is a left side elevation view thereof;

FIG. 5 is a right side elevation view thereof;

FIG. 6 is a rear elevation view thereof;

FIG. 7 is a top plan detail view of the nipple for baby bottle, shown enlarged for clarity of disclosure;

FIG. 8 is a top-front perspective view of a second embodiment of a nipple for baby bottle, showing our new design;

FIG. 9 is a top plan view thereof;

FIG. 10 is a front elevation view thereof;

FIG. 11 is a left side elevation view thereof;

FIG. 12 is a right side elevation view thereof;

FIG. 13 is a rear elevation view thereof; and,

FIG. 14 is a top plan detail view of the nipple for baby bottle of FIG. 8, shown enlarged for clarity of disclosure.
